(57) **CLAIM**

The ornamental design for a water gun, as shown and described.

DESCRIPTION

FIG. 1 is a perspective view of the first component assembled with the third component of a water gun showing my new design;

FIG. 2 is a front view of first component assembled with the third component thereof;

FIG. 3 is a back view of the first component assembled with the third component thereof;

FIG. 4 is a left side view of the first component assembled with the third component thereof;

FIG. 5 is a right side view of the first component assembled with the third component thereof;

FIG. 6 is a top view of the first component assembled with the third component thereof;

FIG. 7 is a bottom view of the first component assembled with the third component thereof;

FIG. 8 is a perspective view of the second component assembled with the third component of a water gun showing my new design;

FIG. 9 is a front view of the second component assembled with the third component thereof;

FIG. 10 is a back view of the second component assembled with the third component thereof;

FIG. 11 is a left side view of the second component assembled with the third component thereof;

FIG. 12 is a right side view of the second component assembled with the third component thereof;

FIG. 13 is a top view of the second component assembled with the third component thereof;

FIG. 14 is a bottom view of the second component assembled with the third component thereof;

FIG. 15 is a perspective view of the first component of a water gun showing my new design;

FIG. 16 is a front view of the first component thereof;

FIG. 17 is a back view of the first component thereof;

FIG. 18 is a left side view of the first component thereof;

FIG. 19 is a right side view of the first component thereof;

FIG. 20 is a top view of the first component thereof;

FIG. 21 is a bottom view of the first component thereof;

(Continued)

FIG. 22 is a perspective view of the second component of a water gun showing my new design;
 FIG. 23 is a front view of the second component thereof;
 FIG. 24 is a back view of the second component thereof;
 FIG. 25 is a left side view of the second component thereof;
 FIG. 26 is a right side view of the second component thereof;
 FIG. 27 is a top view of the second component thereof;
 FIG. 28 is a bottom view of the second component thereof;
 FIG. 29 is a perspective view of the third component of a water gun showing my new design;
 FIG. 30 is a front view of the third component thereof;
 FIG. 31 is a back view of the third component thereof;
 FIG. 32 is a left side view of the third component thereof;
 FIG. 33 is a right side view of the third component thereof;
 FIG. 34 is a top view of the third component thereof; and,
 FIG. 35 is a bottom view of the third component thereof.
